Primary Examiner — Rachel A. Voorhies(74) *Attorney, Agent, or Firm* — Greenberg Traurig, LLP(57) **CLAIM**

The ornamental design for a display device with an animated graphical user interface, as shown and described.

DESCRIPTION

FIG. 1 is a front view of a display device with an animated graphical user interface with a first image in a sequence showing the claimed design.

FIG. 2 is a front view of a second image thereof.

FIG. 3 is a front view of a third image thereof; and, FIG. 4 is a front view of a fourth image thereof.

The outermost broken line illustrates the display device and forms no part of the claimed design. The remaining broken lines illustrate portions of the graphical user interface and form no part of the claimed design.

The appearance of the animated graphical user interface sequentially transitions between the images shown in FIGS. 1-4. The process or period in which an image transitions to another forms no part of the claimed design.
